(57) **CLAIM**

The ornamental design for a truck roof, as shown and described.

DESCRIPTION

FIG. 1 shows a right perspective view of a truck roof; and, FIG. 2 shows a left perspective view and mirror image of the truck roof shown in FIG. 1.

The broken line in the drawing figures shows portions of a truck and forms no part of the claimed design.

1 Claim, 2 Drawing Sheets

FIG 1

FIG. 2
